(57) **CLAIM**

The ornamental design for an exercise strap, as shown and described.

DESCRIPTION

FIG. 1 is a perspective view of the exercise strap showing my new design.

FIG. 2 is a front elevational view of the exercise strap thereof;

FIG. 3 is a rear elevational view of the exercise strap thereof; FIG. 4 is a left side elevational view of the exercise strap thereof;

FIG. 5 is a right side elevational view of the exercise strap thereof;

FIG. 6 is top plan view of the exercise strap thereof;

FIG. 7 is a bottom plan view of the exercise strap thereof; and,

FIG. 8 is a perspective view of the exercise strap shown in use.

The broken lines are shown for environmental use only and form not part of the claimed design.
